UNITED STATES PATENT OFFICE.

WALTER P. MURPHY, OF CHICAGO, ILLINOIS.

SHEET-METAL END STRUCTURE FOR RAILWAY-CARS.

1,313,106.

Specification of Letters Patent. Patented Aug. 12, 1919.

Application filed July 25, 1917. Serial No. 182,767.

To all whom it may concern:

Be it known that I, WALTER P. MURPHY, a citizen of the United States, residing at Chicago, in the county of Cook and State of Illinois, have invented certain new and useful Improvements in Sheet-Metal End Structures for Railway-Cars, of which the following is a specification.

My invention relates to the construction of railway car ends, and has, as its primary object, to provide certain improvements in structures of this character whereby sheet metal end structures for railway cars may be made light in weight without sacrificing the strength and rigidity necessary to resist the various stresses to which car ends are subjected when in service, and whereby the cost of manufacturing such structures may be minimized.

A further and more specific object of my invention is to provide a novel and improved sheet metal end structure for a railway car in which the end sheet is reinforced and rigidified by means of pressed corrugations which extend from one edge of said sheet to the other.

Another object of my invention is to provide an end structure for railway cars comprising novel means for reinforcing the sheet metal end panel and for bracing and rigidifying the side framing of the car. My invention also contemplates the provision of a suitable lining which may be readily applied to structures of the above character and is constructed so that, to a certain extent, it strengthens and reinforces the metal structure of the car end.

My invention has, as a further object, the novel arrangements, constructions and combination of parts hereinafter described and claimed for carrying out the above stated objects and such other objects as may appear from the following description.

My invention is illustrated in certain referred embodiments in the accompanying drawings, wherein—

Figure 1 is an end view, in elevation, of a sheet metal car end structure constructed in accordance with my invention;

Fig. 2, a vertical sectional view taken on line 2—2 of Fig. 1;

Fig. 3, a fragmentary sectional view taken on line 3—3 of Fig. 1;

Fig. 4, a view, in perspective, of one of the

attaching members employed in the structure illustrated in the three preceding figures;

Fig. 5, a view, in elevation, illustrating a modified form of my invention;

Fig. 6, a vertical sectional view taken on line 6—6 of Fig. 5;

Fig. 7, a fragmentary sectional view taken on line 7—7 of Fig. 5;

Fig. 8, a view, in perspective, of one of the attaching members employed in the construction illustrated in Figs. 5, 6 and 7;

Figs. 9 and 10, views similar to Figs. 5 and 6, respectively, illustrating a further modification; and

Fig. 11, a fragmentary sectional view taken on line 11—11 of Fig. 9.

Like characters of reference indicate like parts in the several figures of the drawings.

Referring first to Figs. 1 to 4, inclusive, the structure therein shown consists of an upper end sheet 25 formed with horizontally disposed contiguous ribs or corrugations 26 which extend from side to side of the sheet, a lower sheet 27 similarly corrugated, and side attaching members 28 which are preferably formed with corrugations 29 adapted to fit over the extremities of the corrugations 26 and provided, preferably, with angularly disposed flanges 30 which overlap the side sheathing 31 of the car and are secured to the body by means of bolts 32, for example, which pass through the corner posts 33. The upper sheet is preferably formed with a flat upper margin 34 which is secured by bolts 35 to the end plate 36 of the car. The lower sheet is preferably formed at the bottom with an inturned flange 37 which extends under the flooring of the car and is secured by means of bolts 38 to the end sill 39. The upper sheet overlaps the lower sheet and is secured thereto by rivets 40. The corrugations of the side or attaching members 28 fit closely over the corrugated extremities of the end sheets, the side members being secured to the sheets by rivets 41. As the sheets 25, 27 are formed with continuous corrugations or ribs which extend, in each case, from one side of the sheet to the other, it is possible to perform the operation of corrugating the sheets by cold process without stretching the metal, as would be necessary if the sheets had to be provided with flat or non-corrugated margins at the

sides. Corrugated metal sheets, like sheets designated 25 and 27, may be manufactured by automatic corrugating machines of familiar type. The improvement of my invention, therefore, cheapens the manufacture of ribbed or sheet metal car ends, eliminates the danger of thinning or weakening the sheets incident to subjecting the sheets to a pressing operation when hot, and, furthermore, obviates the warping and distorting often resulting when steel plates or sheets of this character are heated and subjected at different points of their surfaces to unequal pressures. The side members 28 are relatively small so that no difficulty is experienced in dieing them out. The sheets may be made in stock sizes and sheared off at the edge so as to fit cars of different sizes and dimensions. The side members 28, because of their configuration, have considerable load bearing strength so that they may serve as load bearing elements. In this, or analogous constructions in which the attaching angles are separate from the end sheets, it is not necessary to make the end sheets conform in width exactly to the width of the car. Any slight variation in the width of different cars will be taken care of by the overlap of the attaching angles on the end sheets. If thick enough metal is used, the wooden corner posts may be dispensed with or used simply as nailing strips.

In Figs. 1 to 4, inclusive, I have shown a wooden end lining for the sheet metal end illustrated in these figures which lining, while having a particular utility in connection with this particular end construction, might, nevertheless, be used with other corrugated or rib metal end structures as, for example, with the structures shown in the other figures of the annexed drawings. The lining consists of a number of cross pieces 42 which are rounded so as to fit into the cavities formed by the corrugations, and of vertically disposed boards 43 secured to the cross pieces 42. The wooden structure so formed is preferably secured to the sheet metal end by means of bolts 44 which extend through the lining and through the end sheets 25, 27. When the lining is firmly secured to the end sheet in this manner it rigidifies the end and also provides, in effect, a brace extending across the end of the car between the corner posts and thereby rigidifies the car framing. The spacing of the lining from the metal also provides inclosed dead air spaces which act as insulation to prevent the freezing, during severe weather, of that portion of a cargo, vegetables in bulk, for example, which may be in contact with the end.

In Figs. 5 to 8, inclusive, I have shown a construction in which the horizontally corrugated end sheets 46 and 47 are placed between and extend close up to the corner

posts. In this type of end the corrugations are closed by abutting against the attaching or side pieces 48, and the end sheets are arranged between the corner posts 33^a in a manner which makes it unnecessary to use a lining in order to provide a suitable brace for the corner posts or to make the car tight. It may be desirable, however, to use a wooden lining in this construction if the cargo is grain, so as to prevent the grain from coming into contact with the metal. Under such conditions a lining substantially the same as the one shown in Fig. 2 could, obviously, be applied to this construction. The attaching members 48 are formed with corrugated portions 49 which are offset inwardly so that they stand inside the corrugations of the sheets and are also preferably formed with angular flanges 50, and are secured to the car by means of bolts 51 which pass through the corner posts 33^a. This arrangement makes a very strong and rigid structure and one which is perfectly tight.

In Figs. 9, 10 and 11 I have shown another construction in which the end sheets 62, 63, formed preferably, with corrugations 64 which extend, as in the other construction above described, to the edges of the sheets, project beyond the sides of the car and are secured thereto by angular attaching members 65 which are secured to the side of the car by bolts 66 passing through the corner posts 33^b, these angular attaching members being formed with corrugated portions 67 which fit the corrugated margins of the sheets.

This application is a continuation, in part of my co-pending application Serial No. 733,369, filed November 25, 1912, now patent No. 1,236,744, issued Aug. 14, 1917.

I claim:

1. The combination with a railway car, of a sheet metal end structure comprising an end sheet formed with corrugations which extend to one edge of the same and merge one into the other, and a separately formed attaching member provided with corrugations which fit the corrugations of the end sheet and with a flange adapted to be secured to the body of the car.

2. The combination with a railway car, of a sheet metal end structure comprising an end sheet formed with corrugations which extend to one edge of the same and merge one into the other, and a separately formed attaching member provided with corrugations which fit the corrugations of the end sheet, and with a flange extending at substantially right angles to the corrugated portion adapted to be secured to the body of the car.

3. The combination with a railway car, of a sheet metal end structure comprising an end sheet extending across the car from side to side and formed with horizontal corru-

5. 4. The combination with a railway car, of a sheet metal end structure comprising an end sheet extending across the car from side to side and formed with horizontal corrugations which extend to the edges of the sheet and merge one into the other, and attaching members provided with corrugations which fit the corrugations of the end sheet.

10. 5. The combination with a railway car, of a sheet metal end structure comprising an end sheet extending across the car from side to side and formed with horizontal corrugations which extend to the edges of the sheet and merge one into the other, and angular attaching members which fit over the corners of the car body and which are provided with corrugations fitting the corrugations of the end sheet.

15. 6. The combination with the corner posts of a railway car, of an end structure comprising an end sheet overlapping the corner posts and formed with horizontal corrugations extending to the edges of the sheet, angular attaching members formed with corrugations fitting the corrugations of said sheet and with flanges overlapping the sides of the car body, a lining for said end structure consisting of cross pieces fitted into the concavities provided by said corrugations, lining boards secured to said cross pieces, and means for attaching said cross pieces to the end sheet.

20. 7. An end structure for railway cars comprising an end sheet formed with corrugations which extend to the edge thereof and merge one into the other, and a member secured to the car formed with a flat attaching portion and with a corrugated portion to which the corrugated edge of said end sheet is fitted and secured.

25. 8. An end structure for railway cars comprising an end sheet formed with corrugations which extend to opposite edges thereof and merge one into the other, and oppositely disposed members secured to the car formed with corrugated portions to which the corrugated edges of the end sheet are fitted and secured.

30. 9. The combination with the corner posts of a railway car, of an end structure comprising an end sheet overlapping the corner posts and formed with horizontal corrugations extending to the edges of the sheet, and angular attaching members formed with corrugations fitting the corrugations of said sheet and with flanges overlapping the sides of the car body, a lining for said end structure consisting of cross pieces fitted into the concavities provided by said corrugations, lining boards secured to said cross pieces, and means for attaching said cross pieces to the end sheet.

35. 10. The combination with the corner posts of a railway car, of an end structure comprising an end sheet overlapping the corner posts and formed with horizontal corrugations extending to the edges of the sheet, and angular attaching members formed with corrugations fitting the corrugations of said sheet and with flanges overlapping the sides of the car body, a lining for said end structure consisting of cross pieces fitted into the concavities provided by said corrugations, lining boards secured to said cross pieces, and means for attaching said cross pieces to the end sheet.

40. 11. In an end structure for railway cars, the combination with the corner posts of the car, of a sheet metal end wall comprising a sheet metal end panel provided with angular attaching flanges for attaching said panel to said corner posts and end wall, and formed with a plurality of corrugations which merge one into the other so as to form a structure having a sinuous configuration in cross section, and a lining for said structure comprising nailing strips fitted into the concavities of certain of said corrugations and boards extending transversely of said corrugations and secured to said nailing strips.

45. 12. In an end structure for a railway car, the combination with the framing of the car, of a sheet metal end wall comprising a metal panel which extends across the end of the car from one framing member to the other and is formed with a plurality of stiffening corrugations and a wooden lining and reinforcement for said panel comprising strips which are fitted into and secured to certain of said corrugations, and boards extending transversely of said corrugations secured to said strips.

50. 13. In an end structure for a railway car, the combination with the corner posts of the car, of a sheet metal end wall comprising a metal panel extending across the end of the car from corner post to corner post and formed with a plurality of substantially horizontal corrugations and a wooden lining and reinforcement for said panel comprising strips which are fitted into and secured to certain of said corrugations, and vertical boards secured to said strips.

55. 14. The combination with the framing of a railway car, of an end structure comprising a metal end sheet formed with corrugations which extend to the edges of the sheet and attaching members for securing said edges of the sheet to the car framing.

60. 15. The combination with the framing of a railway car, of an end structure comprising a metal end sheet formed with corrugations which extend to the edges of the sheet and angular attaching members each of which has a flange secured to the framing of the car, and a flange to which one of the corrugated edges of the sheet is secured.

65. 16. The combination with the corner posts of a railway car, of an end structure comprising a metal end sheet formed with horizontal corrugations extending to the edges of the sheet, and metal attaching members secured to the corner posts and running

lengthwise thereof to which the corrugated edges of said sheets are secured at intervals.

17. The combination with the corner posts of a railway car, of an end structure comprising a metal end sheet formed with horizontal corrugations extending to the edges of the sheet, and a metal angular attaching member at each side of the car, one flange of which is secured to the corner post of the car and the other at intervals to the adjacent corrugated edge of the end sheet.

18. In combination with the oppositely disposed end framing members of a railway car, of an end wall structure comprising a metal sheet formed with strengthening corrugations and extending across the end of the car from one of said framing members

to the other, and angular attaching elements having flanges overlapping and secured to said frame members respectively and flanges 20 to which the edges of the sheet transverse to the corrugations are secured.

19. In combination with the corner posts of a railway car, of an end wall structure comprising a metal sheet formed with substantially horizontal corrugations and extending across the end of the car from corner post to corner post and angular attaching elements having flanges overlapping and secured to the corner posts and flanges to 30 which the vertical edges of said sheet are secured.

WALTER P. MURPHY.
